UNITED STATES PATENT OFFICE.

JOB W. BLACKHAM, OF BROOKLYN, NEW YORK.

IMPROVEMENT IN HAT-FELTING MACHINES.

Specification forming part of Letters Patent No. 71,959, dated December 10, 1867.

To all whom it may concern:

Be it known that I, JOB W. BLACKHAM, of Brooklyn, in the county of Kings and State of New York, have invented certain new and useful Improvements in Machines for Felting Hat-Bodies; and I do hereby declare that the following is a full and exact description thereof.

My improved machine employs rollers arranged in horizontal layers and revolving together, so as to traverse the hat in one direction along their upper surfaces, while a presser, peculiarly held by springs, is reciprocated backward and forward, as also, if preferred, at certain periods laterally relatively to the motion of the rolls. A tank of water is supported under the rollers, and steam-pipes are immersed in the water, and provided with holes on their upper sides, through which jets of steam issue with sufficient force to throw up the water in a boiling condition against and between the rollers, so as to keep the hat-bodies wet and very thoroughly heated while they are passing over the rollers.

I have in former applications for patents set forth the features above described. The chief peculiarities of my present invention lie, first, in the arrangement of the rollers and the top tables in two sets, so related that the hat-bodies will be carried through one set in one direction and returned through the other set in the opposite direction; second, in the mounting of the reciprocating platforms or pressers on springs, so arranged that the pressure is more lively and less dull and heavy than heretofore; and, third, in a careful proportioning of the velocities of the parts to induce a tighter rolling of the hat-body as it traverses through the machine.

I will now proceed to describe what I consider the best means of carrying out my invention.

The accompanying drawings form a part of this specification.

Figure 1 is a transverse section, and Fig. 2 a longitudinal section, showing a machine constructed according to my invention.

The figures represent the novel parts, with so much of the other parts as is necessary to understand their relations thereto.

A is the frame-work of the machine. N is a broad pan supplied with water, and n is a pipe supplied with steam from a boiler, (not

represented,) which heats and throws up the water, as before intimated. N' is a corresponding pan, mounted directly over the pan N, and similarly supplied with steam.

b is a set of rollers, driven by gearing, arranged as indicated by the red outline, so that all the rollers revolve in the same direction. b' is a corresponding set of rollers similarly driven, but in the opposite direction. The rollers b are mounted immediately over and close to the pan N. The rollers b' are similarly mounted over and close to the pan N'.

C and C' are pressers or rubbers, which reciprocates over the sets of rolls, the presser C working over the lower set of rolls, b, and the presser C' working over the upper set of rollers, b'. The motion of the rolls b carries the hats to the left. The motion of the rollers b carries them in the opposite direction, to the right. There is an operator at each end, who handles the hats, unrolls, and rerolls them, as is necessary. There is a deep vessel, with hot water, at each end, and an inclined surface or "plank," on which the hats are thus re-rolled each time, or as often as is necessary, preparatory to their being passed through the machine in either direction. There are belts J and J' working on pulleys, as represented, or equivalent connections, by gearing or the like, which cause the shaft D and the several sets of rollers to operate in proper relations to each other, the whole being driven by a steam-engine or other suitable motive power through the medium of the gearing or other ordinary mechanical connections. (Not represented.)

F F are levers, turning on the axes f f, and actuated by the links or connecting-rod e' e'', which extend from cranks on the shaft D, as indicated. The levers F F take hold of the reciprocating rubbers C and C' by embracing the pins or arms C' C'', which extend horizontally from each, and stand within slots in the levers F, so that the platforms C and C' are free to rise and sink to a limited extent without interfering with their reciprocating motion. The rolling of the hat-bodies over each of the rolls in the series b and b' causes the reciprocating parts C and C' to be alternately and irregularly lifted and lowered or shaken.

It is very difficult in felting hats by machinery to produce precisely the same effect

on the fibers of the wool or fur as is effected by the hands of a skillful operator. My machine approximates nearer to handwork than any before known to me, and I ascribe the superiority in part to a peculiar mode which I have adopted of mounting the rubbers or platforms C and C'. Each rubber is held up by a strong spring, which is able to more than counterbalance its weight, and is at the same time held down by another spring, which, added to the weight of the rubber or top table, maintains it in the proper position. It follows that the pressure upon the hats is less dead and less violent at any moment than when the weight of the rubber is relied upon to produce the squeezing action. The weight of the rubbers in my machine is comparatively little, and the inertia is trifling. The rubbers, consequently, dance lightly, and act upon the fibers with a different degree of force from what they do when, as in the machines described in my former applications, the weight rests upon the hats, and is only partially balanced by supporting-springs.

A' is a pocket or trough, in which the bodies are dropped and retained as they are discharged from the upper series of rollers and rubbers. A² is a corresponding pocket, in which they are retained when discharged from the lower series.

Many modifications of the forms of the parts may be made without departing from the principle of my invention. I prefer for the rubbers solid surfaces of oak wood, fluted crosswise, as represented; but I believe that a series of rollers properly held can be used for top tables or rubbers. I do not confine myself to any precise number of rollers, nor to the precise mode of working the two rubbers herein described. It is not necessary that the rubbers operate at the same time, one in one direction and the other in the opposite direction. They may both operate together in the same direction, or one may be in its most rapid motion while the other is at rest, or the times of their motion may have various other relations without impairing the result; but there is one point about the motions of the parts which I deem very important, and consider a part of my present invention, which I will now describe.

The upper surfaces of all the rolls in the upper series move toward the left with uniform velocity. The rubber moves horizontally in the same direction and in the reverse direction. Now, I find it important that the velocity of the reverse motion shall be carefully adjusted, so that it shall tend to roll the hat in a tighter roll, instead of loosening it, as is liable to be the case if care is not taken in this regard. My rollers are bunched or covered with beads, which vary the action, so as to approach the condition of the knuckles of the hands; but inasmuch as the depressions be-

tween the beads are of little moment, except to relax the pressure of the rollers at those points, I will consider the diameter in those depressions as of no account, and will give the diameter of the rollers as that of the beads, or the largest parts, which is two and three-quarter inches. The traverse of each top table or rubber is nine inches. The crank D revolves ninety-five times per minute. I have tried several different velocities of rotation of the rollers and find that eighty-five revolutions per minute succeeds admirably. I tried forty-five with a very bad result. The hat-bodies were very sleazy, and in some instances became completely unrolled and issued from the machine detached from the cloth with which they were rolled up. I tried sixty revolutions per minute with a somewhat better result; seventy-five with a still better result, and eighty-five with a result which seems to me perfect. The hats are equal in texture to those felted by the most skillful workman by hand.

I have given the above data, from which other hatters may make their own calculations; but, to generalize the proposition as far as may be, I would say that the forward motion of the top surfaces of the rollers in each bed should be three-sevenths as fast as the quickest part of the reciprocating motion of the top table or rubber which lies thereon. Exactly how the particular relation of the velocities effects the felting of the material I cannot very clearly explain. I do not consider it necessary to do so. It may be sufficient that I have determined the useful result and give the exact proportions and details which I have found successful. It has the effect to deliver the hat-body as tightly rolled up as it entered the machine, care being taken to introduce the hat-body in the right direction, so that the free edge shall be presented, as in Fig. 2.

Having now fully described my invention, what I claim as new in machines for felting hat-bodies, and desire to secure by Letters Patent, is as follows:

1. The duplicate series of rolls b and b', and rubbers C and C', or their equivalents, with their water-pans N N' and jets of hot water or steam, as represented, arranged to operate together in the manner and for the purpose herein specified.

2. Mounting the reciprocating rubber over the bed of rolls, so as to allow of its ascent and descent by means of springs, substantially as and for the purpose herein specified.

In testimony whereof I have hereunto set my hand and seal in presence of the two subscribing witnesses.
